UNITED STATES PATENT OFFICE

137,603

DESIGN FOR A LOUDSPEAKER

Samuel Neville Shaw Mee and Frederick John Toone, Aylestone Park, Leicester, England, assignors to Parmeko Limited, Aylestone Park, Leicester, England, a British company

Application August 24, 1943, Serial No. 110,990
In Great Britain March 6, 1943

Term of patent 14 years

(Cl. D26—14)

To all whom it may concern:

Be it known that we, Samuel Neville Shaw Mee and Frederick John Toone, subjects of the King of Great Britain, residing at Parmeko Works, Percy Road, Aylestone Park, Leicester, England, have invented a new, original and ornamental Design for a Loudspeaker, of which the following is a specification, reference being had therein to the accompanying drawing, forming part thereof.

We claim:

The ornamental design for a loudspeaker, as shown.

SAMUEL NEVILLE SHAW MEE.
FREDERICK JOHN TOONE.
